CLAIM

We claim the ornamental design for an extending camera support, as shown and described above.

DESCRIPTION

FIG. 1 is a front perspective view of the present invention, an extending camera support, in a first orientation;

FIG. 2 is a front elevational view of the extending camera support seen in FIG. 1;

FIG. 3 is a rear elevational view of the extending camera support seen in FIG. 1;

FIG. 4 is a left side elevational view of the extending camera support seen in FIG. 1;

FIG. 5 is a right side elevational view of the extending camera support seen in FIG. 1;

FIG. 6 is a top plan view of the extending camera support seen in FIG. 1;

FIG. 7 is a bottom plan view of the extending camera support seen in FIG. 1;

FIG. 8 is a front perspective view of the present invention, an extending camera support, in a second orientation;

FIG. 9 is a front elevational view of the extending camera support seen in FIG. 8;

FIG. 10 is a rear elevational view of the extending camera support seen in FIG. 8;

FIG. 11 is a left side elevational view of the extending camera support seen in FIG. 8;

FIG. 12 is a right side elevational view of the extending camera support seen in FIG. 8;

FIG. 13 is a top plan view of the extending camera support seen in FIG. 8; and,

FIG. 14 is a bottom plan view of the extending camera support seen in FIG. 8.

The broken lines in each of the figures are for environmental purposes only and form no part of the claimed design.

1 Claim, 8 Drawing Sheets
